United States Patent Office

Des. 196,143
Patented Aug. 27, 1963

196,143

FLEXIBLE PACKAGE FOR CONDIMENTS OR THE LIKE

Eugene J. Kane, Nutley, and Ethel R. McEwan, Teaneck,
N.J., assignors to Thomas J. Lipton, Inc., Hoboken,
N.J., a corporation of Delaware

Filed June 25, 1962, Ser. No. 70,670

Term of patent 14 years

(Cl. D58—2)

We claim:

The ornamental design for a flexible package for condiments or the like, as shown.
